CLAIM

The ornamental design for a removable cover strap for shoe laces, as shown and described.

DESCRIPTION

FIG. 1 is a perspective view of a removable cover strap for shoe laces, showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a side elevational view, the opposite side being a mirror image thereof; and,

FIG. 7 is another perspective view.

The broken line showing of a shoe in FIG. 7 is for illustrative purposes only and forms no part of the claimed design.
